UNITED STATES PATENT OFFICE.

JAMES ALBERT COREY, OF LONDON, ENGLAND.

INTAGLIO PRINTING-PLATE.

1,339,741.

Specification of Letters Patent. Patented May 11, 1920.

Application filed December 24, 1914. Serial No. 878,978.

To all whom it may concern:

Be it known that I, JAMES ALBERT COREY, a subject of the King of Great Britain and Ireland, residing at 18 Manor Mansions, 5 Belsize Grove, Hampstead, London, N. W., England, have invented certain new and useful Intaglio Printing-Plates, of which the following is a specification.

This invention relates to printing by the 10 use of intaglio printing surfaces.

The advantages of intaglio printing surfaces for the effective reproduction of illustration is well known. Such printing surfaces have long since been used for printing 15 in flat-bed printing machines and more recently in rotary printing machines; but their general use for printing in rotary machines is hindered and their utility restricted generally by the difficulty of curving the 20 printing plate without distortion or stretching of the design or image in one direction.

This difficulty alone precludes the employment of rotary printing machines in printing from existing plates, intended for use 25 flat, and carrying designs and images that must be printed with a fine degree of accuracy as to size and proportions—such as ordnance survey maps in one or more colors, postage stamps, or pictures in colors. It is 30 also impracticable to engrave such work on plates so thin that they can be bent without distortion and at the same time be suitable for reproduction by electrotyping.

One of the objects of the invention is thus 35 to render practically possible the duplication of all such flat intaglio or photogravure plates of ordinary thickness in a manner that will permit of curving without distortion.

40 The invention consists of an intaglio printing surface produced in the form of a thin film or plate by electrodeposition. Such a film or plate can be used without any backing or support and can be curved without the printing face appreciably stretching 45 so that thus it may be applied upon a cylinder or cylindrical frame in a rotary printing machine and used for printing whereby perfect register is secured.

50 The invention is diagrammatically illustrated in the accompanying drawings in which—

Figure 1 diagrammatically represents an intaglio printing surface produced according to the invention, and

55 Fig. 2 diagrammatically illustrates a plate

cylinder upon which the intaglio printing surface Fig. 1 may be mounted.

I prepare such films or plates by first producing an original intaglio surface in 60 the flat by any known method, and I then take from the surface a mold in lead or other soft metal or suitable material for the production of a matrix.

The matrix thus produced is used for the 65 production of such films or plates by electrotyping. The electro-type film or plates, however, is deposited by the use of a high current density so as thus to secure a dense, hard and regular deposit of metal and so as 70 thus to produce a thin film or a thin plate which may be subjected to friction in the wiping or scraping of the surface and to the strain imposed during impression without excessive wear and without the possibility of 75 deformation.

I advantageously make first of all upon the matrix a thin deposit of nickel and I then complete the film by the deposit of copper. Any other hard surface may, however, be first electrodeposited upon the matrix.

In carrying the invention into effect according to one method I advantageously employ strips of sheet lead for making the 85 matrices, and these I produce by pressing the lead sheets in contact with the original intaglio engraved surface in any hydraulic press at a pressure of about $\frac{1}{4}$ ton to 2 tons to the square inch. I interpose be- 90 tween the lead sheet and the press a soft resilient layer which may be formed of a number of sheets of a suitable material which extend over the surface of the lead sheet and may be arranged in such manner that the 95 soft resilient layer gradually decreases in thickness or in the number of layers on each side of the part at which the engraved surface occurs, so that thus the lead mold produced has no lines formed upon it nor 100 unevenness of surface, and I effect the molding so that no injury will result to the surface of the original.

The matrix produced will thus be of dimensions corresponding to those of the finished electrotype, or it may be cut down exactly to correspond, the surface being smooth at those parts to which the image does not extend.

The matrix is then used for the produc- 110 tion of an electrotype plate or sheet in the use of a current of high density. The elec-

troyte is maintained in circulation and its specific gravity or degree of concentration maintained uniform as far as practicable so as thus to insure a hard, dense and regular 5 deposit of metal. I prefer to electro-deposit a thin surface of a hard metal, such as nickel and I produce a film of about one-fortieth of an inch in thickness.

Such a film will have its surface smooth 10 where the image does not extend.

The film or thin plate thus produced may be bent around the plate cylinder *b* (Fig. 2) and mounted thereon upon a cylindrical bend in which position it may be fixed, for 15 example, by having its upper and lower edges clamped and by having its edges and the whole of its surface supported upon the cylinder, so that thus a truly cylindrical surface is presented for impression, which may 20 be effectively wiped or scraped.

It will be understood that the electrotype 25 films or thin plates such as *a* thus produced having the image in determined positions thereon and the smooth surfaces where required extending beyond, may be fitted into position in any suitable manner, and they may be produced in any number and of any particular width. It will, however, be understood that thus the image *c* (Fig. 1) 30 may be co-extensive or nearly so with the plates or films. Further it will be understood that by the provision of a thin film or sheet as described it is unnecessary for it to be deformed in its application upon the 35 cylinder or if at all only to a slight extent,

as it readily bends to the extent that is necessary.

I provide the plate-carrying cylinder such as *b* of relatively large diameter, so that if necessary a circular series of films or thin 40 plates may be mounted thereon, or the films or thin plates may be mounted in particular position on the cylinder *b* so that, for example, an eight paged sheet or any other size of sheet may be printed in a single rotation 45 of the plate-carrying cylinder. For example, one page plate may be mounted upon one quarter of the periphery of the plate-carrying cylinder within a suitable recess and seating provided for the purpose, while 50 the other three plates may be mounted in corresponding peripheral positions on the cylinder, which may be of two, four or other pages in width and thus have a plate carrying capacity for eight or sixteen pages. 55

It will be understood that any suitable wiping or scraping mechanism may be employed as to which the present invention is not concerned.

I claim:—

An article of manufacture comprising a 60 dense, flat electrotype intaglio printing plate having a smooth back, said plate being thin and flexible whereby the same may be curved without distortion of the design.

JAMES ALBERT COREY.
